W. S. CLARK.

DESK FIXTURE.

APPLICATION FILED MAR. 25, 1918.

1,332,458.

Patented Mar. 2, 1920.

The diagram shows a mechanical assembly with several numbered parts: 1, 5, 3, 2, 15, 9, 36, 38, 21, 41, 58, 59, 12, 31, 17, 19, 40, 57, 6, 7, 8, and 13. To the right, the text reads "Inventor, Wilbur S. Clark" and "By Joshua R. H. Otto, his Attorney".

UNITED STATES PATENT OFFICE.

WILBUR S. CLARK, OF CAMDEN, NEW JERSEY.

DESK-FIXTURE.

1,332,458.

Specification of Letters Patent.

Patented Mar. 2, 1920.

Application filed March 25, 1918. Serial No. 224,462.

To all whom it may concern:

Be it known that I, WILBUR S. CLARK, a citizen of the United States, residing at Camden, in the county of Camden and State 5 of New Jersey, have invented certain new and useful Improvements in Desk-Fixtures, of which the following is a specification.

One object of my invention is to provide a desk fixture which will be serviceable as 10 an ink-well support and also as a convenient container for pens, pencils, etc.

Another object is to provide my invention with means including movable calendars which are located in such manner as to consecutively reveal the months of the year 15 and the days and the dates of the month.

Another object is to so construct said means that the months, days, and dates can be readily changed from time to time and, if 20 desired, the months of the year may be reversed for consultation of past dates.

A further object is to include in my invention a memorandum strip of paper which can be written upon and readily 25 moved so as to expose a clean portion thereof.

A still further object is to so construct my invention that it will be neat in appearance, can be easily cleaned and will be desirable 30 for use by discriminating persons and on high grade desks.

These objects, and other advantageous ends which will be described hereinafter, I attain in the following manner, reference 35 being had to the accompanying drawings in which—

Figure 1 is a perspective view of my invention,

Fig. 2 is a top plan view of the same, 40 Fig. 3 is a section taken on the line 3—3 of Fig. 2,

Fig. 4 is a section taken on the line 4—4 of Fig. 2, and

Fig. 5 is a section taken on the line 5—5 45 of Fig. 2.

Referring to the drawings, 1 is a casing which is preferably made of glass and is hollow to provide a chamber, as shown at 2, said chamber being open at the bottom. 50 This casing is adapted to rest upon a desk or other supporting structure and has a top portion 3 which is substantially horizontal and includes two depressions or recesses 4 and 5 into which ink-wells may be set.

The portion 3 blends with an inclined

portion 6, said portion 6 terminating at its bottom in a gutter 7. The gutter 7 is convenient for holding pens, pencils, or the like, and terminates at the front in a ledge 60 or flange 8. The casing 1 is preferably made of clear transparent glass which can be molded into the shape illustrated and the inner surface of the glass can be painted or otherwise coated, as shown at 9, with colored 65 material, such for example as red, brown, mahogany, oak, or other colors. This coating is preferably placed over the entire inner surface with the exception of two rectangular portions 10 and 11. In other 70 words, the rectangular portions 10 and 11 will remain transparent, for a purpose hereinafter described.

Two shafts 12 and 13 are journaled in the end portions 14 and 15 of the casing 1. The 75 shaft 12 is made in two telescoping sections 16 and 17. In like manner the shaft 13 is made in two telescoping sections 18 and 19. These sections actually form independent shafts and are provided with knobs 20, 21 80 22, and 23, respectively, whereby they can be independently rotated.

The shaft 16 has a spool 24 secured thereto and on the spool is adapted to be wound a strip 25 of tough paper, fabric, or the like, 85 having a calendar printed thereon, the calendar being divided into separate months, one month following the other throughout the length of the strip 25. The strip is adapted to pass upwardly over an idler 90 roller 26 which is freely rotatable on a shaft 27, the latter being mounted in the end portions 14 and 15. However, it will be understood that the rotation of the idler 26 will not affect or rotate the shaft 27. The 95 strip 25, after passing over the idler 26, is wound on another spool 28 which is secured to the shaft 18. By the rotation of the knobs 20 and 22 this strip can be unwound from one spool and wound on the other. 100

The transparent rectangular portion 10 of the casing is in direct alinement with the width of the strip 25 and the depth of said portion 10 is equal to the depth of each of the months printed on said strip 25. Thus 105 by operating either of the knobs 20 or 22 the different months can be moved into register with the portion 10 so that they can be seen therethrough.

By the arrangement above illustrated and 110 having the transparent portion 10 a part of the inclined portion 6 of the casing 1, the

months can be easily seen by a person sitting at a desk having the fixture thereon, and to advance from one month to another it is merely necessary to turn the knob 22 in the direction of the arrow shown in Fig. 1. If it is desired to consult the dates of a past month, the knob 20 can be rotated in the direction of the arrow shown in Fig. 1, to bring a past month back again into register with the transparent portion 10.

If desired the strip 25 can be printed in a series of months ranging over a number of years and any one of these months can be consulted by turning either the knob 20 or the knob 22.

The shaft 27 has a roller 29 secured thereto and this roller has the days of the week printed thereon. A knob 30 is secured to the shaft 27 on the outside of the casing 1 and said shaft can be rotated thereby to bring the days of the week into register with the left-hand end part of the transparent portion 11. A shaft 31 is journaled at its opposite ends in the end portions 14 and 15 of the casing 1 and has a knob 32 whereby it can be turned.

A roller 33 is fixed to the shaft 31 and a band 34 passes around the roller 33 and up over an idler roller 35 which is loosely mounted on the shaft 27. The band 34 has the dates of the months thereon and is in register with the right-hand end part of the transparent portion 11. By the rotation of the shaft 31 any one of the dates can be brought into alignment with the transparent portion 11 so that by turning the shafts 27 and 31, the day of the week and the date of that day can be brought into alignment and can be seen through the transparent portion 11.

The portion 6 of the casing 1 has two slots 36 and 37 extending therethrough and a strip of memorandum paper 38 is adapted to pass outwardly through the slot 36, then down over the inclined portion 6 and in again through the slot 37. One end of the strip is wound around the spool 39 which is secured to the shaft 17. The other end of the strip is wound around a spool 40 which is secured to the shaft 19. For freedom of

operation the strip 38 passes over an idler roller 41 which is loosely mounted on the shaft 27.

The shafts 17 and 19 can be rotated by turning the knobs 21 and 23 and the strip 38 can thereby be moved in either direction, either to consult recorded memorandum or to bring a clean portion of the strip on the outside of the casing so that a person can write thereon.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A device of the character described including a hollow transparent casing having an inner opaque coating, said coating being discontinued at predetermined portions whereby vision may be had entirely through said portions; and means mounted within said casing and movable so that different parts thereof will be brought into alignment with and can be seen through said portions; substantially as described.

2. A device of the character described including a casing having integral opaque and transparent portions whereby vision may be had through said transparent portions into said casing; and means mounted within said casing and movable so that different parts thereof will be brought into alignment with and can be seen through said portions; substantially as described.

In testimony whereof I have signed my name to this specification in the presence of two subscribing witnesses.

WILBUR S. CLARK.
